UNITED STATES PATENT OFFICE

156,816

TABLE

Morton R. Cohen, Chicago, Ill.

Application December 31, 1948, Serial No. 150,485

Term of patent 14 years

(Cl. D33—14)

To all whom it may concern:

Be it known that I, Morton R. Cohen, a citizen of the United States, residing at Chicago, in the county of Cook and State of Illinois, have invented a new, original, and ornamental Design for a Table, of which the following is a specification, reference being had to the accompanying drawing, forming a part thereof.

I claim:

The ornamental design for a table, as shown.

MORTON R. COHEN.
